UNITED STATES PATENT OFFICE

SOLOMON SHARLIN, OF TRENTON, NEW JERSEY

DESIGN FOR AN ELECTRIC FIXTURE

Application filed December 9, 1929. Serial No. 33,725. Term of patent 3½ years.

To all whom it may concern:

Be it known that I, SOLOMON SHARLIN, a citizen of the United States, and a resident of Trenton, county of Mercer, State of New Jersey, have invented a new, original, and ornamental Design for Electric Fixture, of which the following is a specification, reference being had to the accompanying drawings, forming a part thereof, wherein—

I claim:

The ornamental design for an electric fixture as shown.

SOLOMON SHARLIN.
